UNITED STATES PATENT OFFICE.

JOHN W. PEPPLE, OF HILLSBORO, TEXAS.

COMBINED MAIL CRANE, CATCHER, AND DELIVERER.

No. 923,200.

Specification of Letters Patent.

Patented June 1, 1909.

Application filed July 2, 1908. Serial No. 441,596.

To all whom it may concern:

Be it known that I, JOHN W. PEPPLE, a citizen of the United States, residing at Hillsboro, in the county of Hill and State 5 of Texas, have invented new and useful Improvements in Combined Mail Cranes, Catchers, and Deliverers, of which the following is a specification.

This invention relates to a combined mail crane, catcher and deliverer, and the object 10 thereof is to provide means in a manner as hereinafter set forth, whereby the delivering of the mail can be had simultaneously with the catching of the mail.

Further objects of the invention are to provide a combined mail crane, catcher and deliverer which shall be comparatively simple 15 in its construction, strong, durable, efficient in its use, and comparatively inexpensive to manufacture.

With the foregoing and other objects in view the invention consists of the novel construction, combination and arrangement of parts hereinafter more specifically described 20 and illustrated in the accompanying drawings wherein is shown the preferred embodiment of the invention, but it is understood that changes, variations and modifications can be resorted to which come within the 25 scope of the claims hereunto appended.

In the drawings wherein like reference characters denote corresponding parts throughout the several views:—Figure 1 is a perspective view of a combined catcher 30 and deliverer in accordance with this invention. Fig. 2 is a top plan of a mail crane in accordance with this invention. Fig. 3 is a perspective view showing a mail crane in accordance with this invention and the 35 combined catcher and deliverer in the act of catching and delivering mail. Fig. 4 is a front elevation of the mail crane, and Fig. 5 is a top plan of the combined catcher and deliverer.

Referring to the drawings in detail the 40 combined catcher and deliverer is referred to generally by the reference character 5 and comprises a coupling member 6 which is secured to the side 5^a of the mail car and the 45 said coupling member is provided with two forwardly extending apertured lugs 7 to which is pivotally connected through the medium of the pintles 8 and cotter pins 8^a a swinging supporting arm 9. The latter 50 is formed at its inner end with a pair of laterally extending arms 9^a having aper-

tured ends 10^a through which extend the pintles 8. The other end of the arm 9 is enlarged as at 11 and cut away so as to provide a pair of shoulders 12 which 60 constitute stops. One side of the arm 9 carries a keeper 10 through which extends an elongated bar 13 which is capable of sliding in a longitudinal direction with respect to the arm 9. The bar 13 is cylindrical a major 65 portion of its length and has its outer end as at 13^a secured to a bracket 11^a and its inner end provided with a handle 14. The bracket 11^a straddles the arm 9 and carries a yoke-shaped member formed of a body 70 portion 14^a which terminates at one side in an upwardly extending curvilinear resilient delivery supporting arm 16 and at its other side terminates in a depending curvilinear 75 resilient supporting bar 17. The body portion 14^a of the yoke-shaped member is secured to the bracket by suitable fastenings as shown. The bracket 11 is formed with a rearwardly extending inclined hook 15 which constitutes a catcher for a sack or 80 pouch. Each of the arms 16 and 17 has a hook-shaped end 18 and an arrester lug 18^a, the function of which will be hereinafter referred to. The bar 13, bracket 11, hook 15 and yoke-shaped member carried by the 85 bracket constitutes what is termed a combined mail pouch catching and delivering means. The bar 13 is termed a shiftable carrier.

A means is provided for maintaining the 90 supporting arm 9 the necessary distance from the side 5^a of the car and to which is pivotally connected as at 18^a a lever arm 18^e which is articulated as at 18^b to a link 18^m, the latter being pivoted as at 18ⁿ to a bracket 18° secured to the inner face of the arm 9. A handle 18^w is attached to the lever 18^e whereby the said means can be conveniently extended to maintain the arm 9 in the desired 95 position and contracted when it is desired 100 to swing the bar toward the side of the car after the catching and delivering action.

The crane comprises a vertically extending post 19 having extending at right angles 110 with respect thereto a pair of hangers arranged in vertical alinement with respect to each other, one end of each of these

hangers being fixed to the post 19, the upper of the hangers projecting from the top of the post and the lower of the hangers being positioned at a point intermediate the 5 ends of the post. The upper hanger comprises a body portion 20 which terminates in a pair of diverging arms which are indicated by the reference characters 20^a and 20^b. Each of the diverging arms is formed 10 with a concaved end 20^c and a stop 20^d. The lower hanger is formed with a body portion 21 which terminates in a pair of diverging arms 21^a and 21^b. The arm 21^a has its outer terminus formed in a convex manner as at 21^c and the arm 21^b is constructed 15 in a similar manner as at 21^d. Stops 21^d depend from the lower face of the arms 21^a and 21^b. The arm 20^b is arranged in vertical alinement with respect to the arm 21^b 20 and a like arrangement is had in connection with the arm 20^a with respect to the arm 21^a. The hangers are adapted to support the pouch or sack 22 and the stops 20^d and 21^d are adapted to prevent the rings 23 25 from sliding inwardly upon the converging arms. The terminus 20^c of the arm 20^a and the terminus 21^c of the arm 21^a are adapted to support the sack when the train is traveling in one direction and the terminus 20^c of 30 the arm 20^b and the terminus 21^d of the arm 21^b are adapted to support the sack when the train is traveling in the opposite direction. Secured to the post 19 at a point intermediate its ends and between the hangers 35 is an inverted triangular shaped bracket 24 having a supporting ledge 24^a upon which is adapted to rest a sectional angle-shaped receiver and which comprises an inner horizontally extending arm 25 and an outer supporting arm 26 which extends at 40 an inclination with respect to the arm 25. One end of the arm 26 is hinged to one end of the arm 25, the hinge being indicated by the reference character 27. The other end 45 of the arm 26 is provided with a rearwardly extending inclined hook 28, the hook being somewhat curvilinear in contour. The arm 25 is pivotally connected as at 29^a to the post 19 above the ledge 24^a. By setting up 50 the receiver in the manner as stated, it can be shifted so as to extend from either side of the post 19, whereby provision is made for receiving the sack with respect to the direction in which the train is traveling. 55 Interposed between the arms 25 and 26 is a coiled spring 29, the function of which is to maintain the arm 26 away from the arm 25 and further to constitute a cushioning means when the receiver is taking up the 60 sack or pouch. Steps 30 and a platform 31 are provided to enable the mail pouch to be conveniently placed upon the crane and to remove that mail pouch which has been caught by the receiver.

65 The resilient arms 16 and 17 are adapted

to support the pouch when it is desired to deliver the same to the receiver. The hook-shaped ends 18 of the arms 16 and 17 are provided to prevent the pouch from accidentally slipping off or being removed from the arms during the act of delivery. These hooked ends, however, will not prevent the removal of the sack from the arms 16 and 17 when the sack comes in contact with the hook of the receiver, for the reason that the arms 16 and 17 are somewhat resilient and will readily give during the operation of stripping the pouch through the medium of the hook of the receiver. This is clearly shown in Fig. 3. Although the diverging arms of the hangers will cause the pouch to be maintained in the position shown in Fig. 3, that is to say supported by the crane, yet this element will not interfere with the removal of the pouch when it is engaged by the hook 15 of the combined deliverer and catcher. The shift bar 13 is provided to allow of the same being moved inwardly to facilitate the mounting of the pouch upon the arms 16 and 17 and to facilitate the removal of the pouch when it is caught by the hook 15. The bar 13 can also be projected so as to position the pouch to be stripped by the hook of the receiver. If it be desired, however, the bar 13 can be dispensed with and the hook 15 and arms 16 and 17 secured to the outer end of the arm 9. As before stated, the receiver owing to the manner in which it is set up is reversible so as to provide for the receiving 100 of the pouch in the direction in which the train is traveling. The bracket 24 is of sufficient length so as to offer the necessary support for the arm 25 when projecting from either side of the post 19.

105 What I claim is:—

1. A mail pouch delivering and catching apparatus, comprising a swinging arm adapted to be secured to the mail car, a shiftable bar slidably mounted upon said arm, a pair of resilient mail pouch supporting arms fixed to said bar, and a laterally extending hook secured to the bar.

2. A mail pouch delivering and catching apparatus, comprising a swinging arm adapted to be secured to the mail car, a shiftable bar slidably mounted upon said arm, a pair of resilient mail pouch supporting arms fixed to said bar, and a laterally extending hook secured to the bar, combined with a receiver arm provided at one end with a hook, said hook adapted to be positioned in the path of the pouch carried by the supporting arms.

3. A mail pouch delivering and catching apparatus, comprising a swinging arm adapted to be secured to the mail car, a shiftable bar slidably mounted upon said arm, a pair of resilient mail pouch supporting arms fixed to said bar, a laterally ex- 130

tending hook secured to the bar, and a stop for limiting the movement in one direction of said shiftable bar.

4. A mail pouch delivering and catching apparatus, comprising a swinging arm adapted to be secured to the mail car, a shiftable bar slidably mounted upon said arm, a pair of resilient mail pouch supporting arms fixed to said bar, a laterally extending hook secured to the bar, and a stop for limiting the movement of said shiftable bar, combined with a receiver arm having one end provided with a hook adapted to be positioned in the path of the pouch carried by the supporting arms.

5. A device of the character described comprising the combination with a mail crane, a reversible receiver arm hinged thereto and provided with a hooked end and a support for said arm, of a swinging arm pivoted to the mail car, a shiftable bar slidably mounted upon said swinging arm, an inwardly extending hook carried by the outer end of said bar, and a pair of resilient mail pouch supporting arms secured to the outer end of said shiftable bar.

6. A device of the character described comprising the combination of means for supporting a mail pouch, of means carried by the car for catching the pouch, said last mentioned means provided with pouch supports for delivering a pouch from the car, and a cushioned receiving and stripping means for the pouch upon those supports forming a part of the means carried by the car.

7. A device of the character described comprising the combination of means for supporting a mail pouch, of means carried by the car for catching the pouch, said last mentioned means provided with pouch supports for delivering a pouch from the car, and a cushioned receiving and stripping means for the pouch upon those supports forming a part of the means carried by the car, said receiving and stripping means mounted upon the first mentioned means for supporting the mail pouch.

8. A device of the character described comprising the combination of means embodying two pairs of arms, the arms of each pair arranged in vertical alinement and adapted to support a mail pouch, of means carried by a car for catching the pouch supported by one pair of arms, said last-mentioned means provided with pouch supports for delivering a pouch from the car, and a receiving and stripping means for the pouch carried by those supports forming a part of the means carried by the car.

9. A device of the character described comprising the combination of means embodying two pairs of arms, the arms of each pair arranged in vertical alinement and adapted to support a mail pouch, of means

carried by a car for catching the pouch supported by one pair of arms, said last mentioned means provided with pouch supports for delivering a pouch from the car, and a reversible receiving and stripping means for the pouch carried by those supports forming a part of the means carried by the car.

10. A device of the character described comprising the combination of means embodying two pairs of arms, the arms of each pair arranged in vertical alinement and adapted to support a mail pouch, of means carried by a car for catching the pouch supported by one pair of arms, said last-mentioned means provided with pouch supports for delivering a pouch from the car, and a cushioned receiving and stripping means for the pouch carried by those supports forming a part of the means carried by the car.

11. A device of the character described comprising the combination of means embodying two pairs of arms, the arms of each pair arranged in vertical alinement and adapted to support a mail pouch, of means carried by a car for catching the pouch supported by one pair of arms, said last mentioned means provided with pouch supports for delivering a pouch from the car, and a reversible cushioned receiving and stripping means for the pouch carried by those supports forming a part of the means carried by the car.

12. In a mail pouch delivering and receiving apparatus, in combination, an arm formed of two horizontally disposed sections hingedly connected at adjacent ends, cushioning means interposed between said sections, one of said sections being movable on the hinge joint, and a mail pouch engaging and catching device on the free end of the movable section.

13. In a mail pouch delivering and receiving apparatus, in combination, an arm comprising a pivotally mounted section, a section hinged to the end of the pivotally mounted section and movable on its hinge joint, the last named section carrying a mail pouch catching device, and means for supporting the first named section in a horizontal position.

14. In a mail pouch delivering and receiving apparatus, in combination, an arm formed of two horizontally disposed sections hingedly connected at adjacent ends, an expansive coil spring interposed between said sections, one of said sections being movable on the hinge joint and a mail pouch engaging and catching device on the free end of the movable section.

15. In a mail pouch delivering and receiving apparatus, in combination, a pivotally mounted arm movable on its pivot to either of two opposite horizontal positions, means for supporting said arm in either of said horizontal positions and a mail pouch

catching device carried by said arm and operative in either of the horizontal positions of said arm.

16. In a mail pouch delivering and receiving apparatus, in combination, a supporting arm carried upon the mail car and mounted to stand out horizontally therefrom, a bar associated with said arm and movable longitudinally thereof, mail pouch catching means carried by said bar and mail pouch holding means carried by said bar.

17. In a mail pouch delivering and receiving apparatus, in combination, mail pouch receiving means comprising a relatively stationary supporting member, a member carried by the stationary member, movable with respect thereto and provided with a mail pouch engaging device, and cushioning means interposed between said members to take up the shock incident to the engagement of a mail pouch with said device.

18. In a mail pouch delivering and receiving apparatus, in combination, a hori-

zontally disposed arm carried by the car 25 and having at one end thereof, a mail pouch holding means projecting in one direction and a mail pouch receiving means projecting in an opposite direction, and a member shiftable longitudinally of the arm and carrying 30 both of said means.

19. In a mail pouch delivering and receiving apparatus, in combination, a crane having two mail pouch supporting means distant from one another and a member having 35 mail pouch receiving means associated therewith and movable to operative positions in which the said mail pouch receiving means is adjacent either of said supporting means.

In testimony whereof I have hereunto set my hand in presence of two subscribing witnesses.

JOHN W. PEPPLE.
